CONTROL APPARATUS FOR RAILWAY SWITCHES

William C. McWhirter, Wilkinsburg, Pa., assignor to The Union Switch & Signal Company, Swissvale, Pa., a corporation of Pennsylvania

Application December 31, 1931
Serial No. 534,100

12 Claims. (Cl. 246—411)

My invention relates to control apparatus for railway switches, and has for an object the provision of a switch lock with point detector which is adapted for use in connection with any of the well-known forms of manually operable switch throwing devices, and which when so used will increase the safety of trains or vehicles moving over the switch.

I will describe one form of apparatus embodying my invention, and will then point out the novel features thereof in claims.

In the accompanying drawings, Fig. 1 is a top plan view showing a railway switch provided with a switch lock embodying my invention. Fig. 2 is an end view of the apparatus shown in Fig. 1. Fig. 3 is a top plan view, showing on an enlarged scale, the switch lock C illustrated in Figs. 1 and 2, the cover of the lock being removed, and certain of the parts being broken away to better illustrate the construction. Fig. 4 is a vertical longitudinal sectional view of the switch lock C shown in Fig. 3. Fig. 5 is an end view, partly in section, and partly in elevation, of the lock shown in Figs. 3 and 4, certain of the parts being broken away or removed to better illustrate the construction thereof. Fig. 6 is a sectional view on the line VI—VI of Fig. 5. Fig. 7 is a detail view showing the locking hasp 42 for at times locking the foot pedal 37 in its normal position. Fig. 8 is a sectional view taken on the line VIII—VIII of Fig. 4.

Similar reference characters refer to similar parts in each of the several views.

Referring first to Fig. 1, the reference character A designates a railway switch, and the reference character B designates a device for operating it. The switch A is of the ordinary and well-known construction, and comprises the usual stock rails 1 and 1^a, and movable switch points 2 and 2^a, the switch points being connected for simultaneous movement by a head rod 3 and a front rod 4.

The operating device B, in the form here shown, comprises a switch stand 5, having its base 5^a spiked or otherwise secured to the ties adjacent the switch A. A gear shaft 6 is journaled in the switch stand 5 and carries a crank 7, and a gear segment 8. The crank 7 is connected with the head rod 3 of switch A by means of a link 9 and a throw rod 10. The gear segment 8 meshes with a bevel pinion 11 keyed to a pinion shaft 12. The pinion shaft 12 extends through the side of the switch stand 5 and has attached to its outer end the usual hand throw lever 13.

The apparatus thus far described is well-known in the art, and its operation will be readily understood from an inspection of the drawings.

Attached to the front rod 4 of the switch A is the usual lock rod 14, and attached to the switch point 2^a by means of a bracket 15 is the usual adjustable point detector rod 16. The lock rod 14 and the point detector rod 16 both extend underneath the rail 1^a and, as here shown, cooperate at their free ends with a combined switch lock and point detector C embodying my invention, which switch lock also cooperates with the hand throw lever 13 of the switch operating device B, as will be explained fully hereinafter.

Referring now also to Figs. 3 to 7, inclusive, the switch lock C embraces a suitable casing which, in the form here shown, comprises a main housing 17 and two auxiliary housings 18 and 19 which are attached to the main housing 17. The main housing 17 is intended to be secured to a railway tie or other convenient support adjacent the switch operating device B, and for this purpose, this housing is provided with apertured feet 20 through which lag screws or other suitable fastening devices may be passed. A cover 21, hinged to the main housing 17 by means of lugs 22, one of which is shown in Fig. 4, normally closes the upper end of this housing, but permits convenient access to the interior of the housing for inspection or repair of the mechanism. The cover 21 is adapted to be fastened in its closed position by means of a suitable fastening device 23 which is slotted to receive an eye 23^a secured to the cover 21.

As best seen in Fig. 4, a horizontally extending rectangular guideway 24, formed in part in the main housing 17, and in part in the auxiliary housing 19, slidably receives the free end 95 of the previously described lock rod 14, and a circular guideway 25 formed in the auxiliary housing 19 slidably receives the free end of the point detector rod 16. The lock rod 14 is provided with a hole 14^a which, when the switch 100 occupies its full normal position in which it is shown in the drawings, registers with two aligned holes 28 and 29 formed in the main housing 17, and in the auxiliary housing 19, respectively. Extending into the holes 28 and 29 and cooperating with the hole 14^a in the lock rod 14 for at times locking the switch A in its normal position, is one end of a locking plunger 26, the other end of which is slidably mounted in a bracket 27 secured to the bottom of the main 110

housing 17. The locking plunger 26 is constantly urged into engagement with the lock rod 14 by means of a coil spring 30 which surrounds the locking plunger between the bracket 27 and a washer 31 which abuts against a pin 32 carried by the plunger. The pin 32 extends horizontally through the locking plunger at right angles to the axis of the plunger, and is spaced from a second similar pin 33, one function of which is to limit the movement of the plunger toward the left as viewed in Fig. 4 when the plunger is within the hole 14^a in the lock rod 14. A lever 34 is operatively connected at one end with the locking plunger 26 by means of integral bifurcations 34^a and 34^b which extend downwardly on opposite sides of the plunger between the pins 32 and 33 to a point past the horizontal axis of the plunger. The other end of the lever 34 is fixed to a horizontally extending rockshaft 35 which is journaled in bearings 36 formed in the side walls of the housing 17. The rockshaft 35 projects through the housing 17 and is provided at one end with a foot pedal 37 (see Fig. 3). It will be seen that by depressing the foot pedal 37, the rockshaft 35, and hence the lever 34, may be rotated in a counter-clockwise direction as viewed in Fig. 4, thus causing the locking plunger 26 to move toward the right in opposition to the bias of the spring 30 to the position in which the locking plunger is out of engagement with the hole 14^a in the lock rod 14.

The end of the rockshaft 35 opposite to that to which the foot pedal 37 is attached extends into the auxiliary housing 18, and has fixed thereto a locking segment 38 which cooperates with a lever latch 39, as best seen in Figs. 5 and 6. The lever latch 39 is pivoted on a pin 40 carried by two vertical standards 41 formed on an extension 18^a of the auxiliary housing 18, and is provided with a horizontal arm 39^a and a vertical arm 39^b. The horizontal arm 39^a extends into the housing 18 through an opening 18^b and cooperates at its inner end with a cam 38^a formed on the locking segment 38, in such manner that when the foot pedal 37 occupies its normal position, the lower edge of the cam 38^a will engage the upper side of the arm 39^a and hold the lever latch in its normal position in which it is shown in full lines in Fig. 5, but that, when the foot pedal 37 is depressed, the lever latch 39 will then be free to rotate to the position in which it is shown in dot and dash lines in Fig. 5. The vertical arm 39^b of the lever latch 39 is provided with a nose 39^c which, when the hand throw lever 13 occupies its normal position in which it is shown in the drawings, and the lever latch occupies its normal position, overlies the hand throw lever. It will be seen therefore that the hand throw lever cannot be raised to operate the switch from its normal position unless the foot pedal 37 is first depressed to move the cam 38^a out of engagement with the horizontal arm 39^b of the lever latch. It will also be seen that, due to the shape of the nose 39^c on the vertical arm 39^b of the lever latch, when the hand throw lever is raised to reverse the switch A, the lever latch will be automatically operated to its dot and dash line position. The lever latch is so designed that when it is once moved to its dot and dash line position, it will be held in this position by gravity until the hand throw lever is again restored to its normal position, at which time the hand throw lever will engage the upper side of the arm 39^a of the lever latch

and rotate the lever latch to its normal position.

As best seen in Figs. 5 and 7, the foot pedal 37 is provided with a downwardly projecting lug 47 which cooperates with a locking hasp 42 for at times locking the foot pedal in its normal position. The locking hasp 42 is pivoted at its lower end on a pin 43 carried by a lug 44 formed on a plate 45 attached to the outer side of the main housing 17 directly below the foot pedal 37, and is provided in its upper end with a recess 46 which is adapted to receive the lug 47. It will be apparent that when the locking hasp occupies the position in which the lug 47 is within the recess 46 as shown in Fig. 5, rotation of the foot pedal 37 is prevented. The foot pedal may be released, however, by rotating the locking hasp in a clockwise direction as viewed in Fig. 5 from its full line position in which it engages the lug 47 to its dot and dash line position in which it is out of engagement with the lug 47. The lug 47 is provided with an eye 47^a through which a padlock 48 or other suitable locking device may be passed. It will be seen that when the padlock 48 is within the eye 47^a, and the hasp 42 and foot 100 pedal 47 are in the relative positions shown, the hasp cannot be rotated to the position in which it is out of engagement with the lug, and it follows, therefore, that under these conditions, the foot pedal is locked in its normal 105 position.

As best seen in Fig. 4, a lever 49 is pivotally mounted on a pin 50 carried by the bracket 27, and is provided with a roller 51 which cooperates with the chamfered end 26^a of the locking plunger 26. The lever 49 is also provided with downwardly extending fingers 49^a which straddle the locking plunger 26, and which cooperate with a transverse pin 52 extending through the locking plunger at right angles to the axis of the plunger. An operating member 53 is pivotally attached to the lever 49 at 77, and is guided to move vertically by means of studs 75 which pass freely through holes 76 in the operating member. The operating member 120 53 actuates a circuit controller, designated as a whole by the reference character D.

The circuit controller D may be of any suitable type, but as here shown, this circuit controller comprises two contact members 54 and 55 (see Fig. 4) attached to the opposite sides of an insulating block 58 by means of terminal posts 56 and 57. The insulating block 58 is supported on lugs 59 projecting inwardly from the sides of the housing 17. The terminal post 56 is electrically connected with the contact member 55, but is insulated from the contact member 54, as will be apparent from an inspection of the drawings, and the terminal post 57 is electrically connected with the contact member 54, but is insulated from the contact member 55. One end of the contact member 55 is formed with an integral relatively rigid contact finger 55^a, and the corresponding end of the contact member 54 is formed with an integral relatively flexible contact finger 54^a which cooperates with the contact finger 55^a to form a contact 54^a—55^a. The movable contact finger 54^a is clamped between two insulating blocks 60 and 61 which are attached to the operating member 53 by means of suitable screws. The parts are so proportioned that when the locking plunger is within the notch 14^a in the lock rod 14 as shown in the drawings, the pin 52 will engage the fingers 49^a on the lever 49, and will rotate the lever 49 to the position in 145 150

which the contact 54^a—55^a is held open by the operating member 53.

The contact member 55 is also formed with a second relatively rigid contact finger 55^b, and the contact member 54 is likewise formed with a second relatively flexible contact finger 54^b which cooperates with the contact finger 55^b to form a contact 54^b—55^b. The contact finger 54^b is engaged by an insulating block 78 carried by an operating yoke 64. As best seen in Fig. 3, the operating yoke 64 comprises two spaced arms 64^a and 64^b joined at one end by a connecting member 64^c which carries the insulating block 78. The arms 64^a and 64^b are pivoted on studs 65 screwed into the side wall of the housing 17, and the free ends of these arms are provided with counterweights 66 which bias the operating yoke to the position in which the contact 54^b—55^b is open, as shown in Fig. 4. The yoke 64 is operated by a lever 67 which is journaled intermediate its ends on the rock shaft 35. One end of the lever 67 engages a lug 64^d (see Figs. 3 and 4) formed on the connecting member 64^c of the yoke 64, and the other end of the lever 67 enters a recess 68 formed in the upper end of a plunger rod 70. The plunger rod 70 is slidably mounted in a vertical guideway 71 formed in the auxiliary housing 19, and is provided at its lower end with a roller 72 which cooperates with an annular notch 73 formed in the point detector rod 16. A pin 74 carried by the plunger rod 70 acts as a stop to limit the downward movement of the plunger rod to the desired amount.

The circuit controller D may comprise any suitable number of sets of contact members 54 and 55, four such sets being shown in Figs. 3 and 4. The corresponding contact members of each set are connected together by means of conducting strips 79 which are electrically connected to the terminal posts 56 and 57 as shown in Figs. 3 and 5.

In explaining the operation of the apparatus as a whole, I will assume that the parts are all in their normal positions in which they are shown in full lines in the drawings, and in which switch A is locked, and that it is desired to reverse the switch points. To do this, the padlock is first removed from the eye 47^a in the lug 47 on the foot pedal 37, and the locking hasp 42 is then rotated in a clockwise direction, as viewed in Fig. 5, to the position in which the locking hasp is clear of the lug 47 on the foot pedal 37. The foot pedal 37 is next depressed. As previously pointed out, when the foot pedal 37 is depressed the locking plunger 26 is moved to the right, as viewed in Fig. 4, to the position in which it is out of engagement with the hole 14^a in the lock rod 14, and at the same time the locking segment 38 is rotated in a clockwise direction, as viewed in Fig. 6 to the position in which the cam 38^a is out of the path of movement of the inner end of the horizontal arm 39^a of the lever latch 39. The movement of the locking plunger 26 out of the notch 14^a in the lock rod 14 unlocks the switch points, and in addition, due to the coaction between the chamfered end 26^a of the locking plunger 26 and the roller 51 carried by the lever 49, causes the lever 49 to rotate in the direction to raise the operating member 53 and close the contacts 54^a—55^a of circuit controller D. The parts of circuit controller D are so arranged and so proportioned that the contacts 54^a—55^a will become closed before the locking plunger has been completely withdrawn from the hole 14^a in the

lock rod 14. The lever latch once having been released, the hand throw lever 13 may be operated to reverse the switch points in the usual manner. When this is done, the lever latch 39 is automatically rotated to its dot and dash line position, and is subsequently held in this position by gravity and friction. In this latter position of the lever latch, the arm 39^a thereof engages the right-hand edge 38^a of the cam 38, as viewed in Fig. 6, and thus holds the rockshaft 35 in the position to which it was moved by depressing the foot pedal. As a result, the foot pedal 37 may be released as soon as the hand throw lever has been raised a small amount from its normal position, and the plunger rod 26 will then remain out of engagement with the lock rod 14 so that the contacts 54^a—55^a of circuit controller D will continue to remain closed as long as the lever latch remains in its dot and dash line position which will normally be until the hand throw lever 13 is returned to its normal position. The movement of the switch points to their reverse positions moves the point detector rod 16 toward the left as viewed in Figs. 3 and 5 to the position in which the notch 73 is out of alignment with the roller 72 on the plunger rod 70, thus forcing the plunger rod upwardly, and hence rotating the lever 67 in a clockwise direction about the shaft 35 as viewed in Fig. 4. The clockwise rotation of the lever 67 forces the operating yoke 64 downwardly in opposition to the bias of the counterweights 66, thus closing the contacts 54^b—55^b of circuit controller D.

When it is desired to again restore the parts to the position shown, the hand throw lever 13 is restored to its normal position. This automatically moves the lever latch 39 to the position in which the arm 39^a is out of engagement with the side of the cam 38^a of locking segment 38, and hence releases rockshaft 35. As a result, if the hole 14^a in the lock rod 14 then aligns properly with the holes 28 and 29 in the housings 17 and 19, as will be the case when the switch points have not been damaged due, for example, to an improper trailing movement, the spring 30 will automatically return the locking plunger 26 to the position in which it enters the hole 14^a. This movement of the locking plunger will restore the foot pedal to its normal position and, due to the coaction between the pin 52 and the fingers 49^a on lever 49, will also rotate lever 49 in the direction to open the contacts 54^a—55^a of circuit controller D. With the switch points in their normal positions, the notch 73 in the lock rod 16 will again align with the roller 72 on the plunger rod 70, and the plunger rod 70 will therefore assume the position shown in Fig. 5, thus permitting the counterweights 66 to rotate the operating yoke 64 to the position in which the contacts 54^b—55^b of circuit controller D are open. The foot pedal having been restored to its normal position, may now be locked in this position by rotating the hasp 42 to the position shown in Fig. 5 and inserting the padlock 48 in the eye 47. All parts will then be locked in their normal positions.

The contacts of the circuit controller D may be utilized to shunt a track circuit for the control of automatic signals in a manner well-known in the art or for any other desired purpose.

It will be readily understood from the foregoing and from an inspection of the drawings that, should the lever latch 39 be improperly

manipulated when the switch points have been reversed by the hand throw lever so as to move the lever latch from its dot and dash line position to its normal position, it would merely release the rockshaft 35 and permit the spring 30 to bring the end of the locking plunger up against the lock rod 14. This movement of the locking plunger is insufficient to open the contacts 54^a—55^a of circuit controller D and it will be seen, therefore, that no dangerous condition would exist under these conditions. The hand throw lever 13 can, under these conditions, be readily restored to its normal position because, due to the shape of the nose 39^c on the arm 39^b of the lever latch 39 the hand throw lever upon engaging the arm 39^b will automatically rotate the lever latch to its dash line position provided foot pedal 37 is then depressed.

It will also be readily understood from the foregoing, and from an inspection of the drawings, that any improper position of the switch points due for example to a train trailing through the switch when the switch is locked in its normal position will move the point detector rod 16 to the left, as viewed in Fig. 5, a sufficient distance to force the plunger rod 70 out of the notch 73, thus closing the contacts 54^b—55^b of circuit controller D, and hence indicating the improper operation.

One advantage of a switch lock embodying my invention is that it provides mechanical locking for the switch points, a means for detecting through the medium of electrical contacts the position of the switch points with respect to the stock rail, and a means for padlocking the entire device as well as the hand throw lever of the switch operating device B, all in one mechanism.

Although I have herein shown and described only one form of control apparatus for railway switches embodying my invention, it is understood that various changes and modifications may be made therein within the scope of the appended claims without departing from the spirit and scope of my invention.

Having thus described my invention, what I claim is:

1. The combination with the movable points of a railway switch and a hand throw lever for moving the switch points, of a lock rod connected with the switch points to move therewith, a locking plunger biased into engagement with said lock rod and cooperating with the lock rod for at times locking the switch points in one position, means for at times moving said locking plunger in opposition to its bias to unlock the switch points, means for preventing movement of the hand throw lever to move the switch points from said one position except when the switch points are unlocked, and a contact controlled by said locking plunger and arranged to be operated when said switch points are unlocked but not when said switch points are locked.

2. The combination with the movable points of a railway switch and a hand throw lever for moving the switch points, of a lock rod connected with the switch points to move therewith, a locking plunger biased into engagement with said lock rod and cooperating with the lock rod for at times locking the switch points in one position, foot operated means for at times moving said locking plunger in opposition to its bias to unlock the switch points, means for preventing movement of the hand throw lever to move the switch points from said one position

except when the switch points are unlocked, a contact, and means for operating said contact when said plunger is moved in opposition to its bias by said foot operated means.

3. The combination with the movable points of a railway switch and a hand throw lever for moving the switch points, of a lock rod connected with the switch points to move therewith, a locking plunger biased into engagement with said lock rod and cooperating with the lock rod for at times locking the switch points in one position, means for at times moving said locking plunger in opposition to its bias to unlock the switch points, means for preventing movement of the hand throw lever to move said switch points from said one position except when the switch points are unlocked, a contact, and means for operating said contact if said switch points are trialed when they are locked in said one position.

4. The combination with the movable points of a railway switch and a hand throw lever for moving the switch points, of a lock rod attached to said switch points and provided with an opening, a switch lock comprising a casing, a guide-way formed in said casing and slidably receiving said lock rod, a locking plunger slidably mounted in said casing, means for biasing said locking plunger to a position in which said locking plunger will enter said opening in said lock rod when said switch points are in their normal positions, a rockshaft journaled in said casing, a lever fixed to said rockshaft and operatively connected with said locking plunger, a foot pedal fixed to said rockshaft, a lever latch for controlling the movement of the hand throw lever, and a locking segment secured to said rockshaft and provided with a cam for controlling the movements of the lever latch.

5. The combination with the movable points of a railway switch and a hand throw lever for moving the switch points, of a lock rod attached to the switch points for movement therewith and provided with an opening, a point detector rod secured to one switch point for movement therewith and provided with a notch, a plunger rod cooperating with the notch in said point detector rod, a locking plunger biased to a position in which said locking plunger will enter the opening in said lock rod when said switch points are in their normal positions, a lever latch, means for at times locking said lever latch in one position, said lever latch being adapted to prevent movement of said hand throw lever to move said switch points from their normal positions when said lever latch is locked in said one position, means for simultaneously withdrawing said locking plunger from the opening in said lock rod and for unlocking said lever latch, and a circuit controller controlled jointly by said plunger rod and said locking plunger.

6. The combination with the movable switch points of a railway switch and a hand throw lever for moving the switch points, of means for separately locking the switch points and the hand throw lever simultaneously, a foot pedal for controlling said locking means, a lug on said foot pedal provided with a hole for the reception of a locking device, and a pivoted locking hasp provided with a recess adapted to receive said lug and so arranged that said hasp may be maintained in engagement with said lug by placing the locking device in said hole.

7. The combination with the movable switch

- points of a railway switch and a hand throw lever for moving the switch points, of a lever latch for controlling the movements of the hand throw lever, a lock rod connected with the switch points for movement therewith, a locking plunger cooperating with the lock rod for locking the switch points in one position, a foot pedal for controlling said lever latch and said locking plunger, and a contact arranged to be operated when said foot pedal is operated. 80
8. The combination with the movable switch points of a railway switch and a hand throw lever for moving the switch points, of a lever latch for controlling the movements of the hand throw lever, a lock rod connected with the switch points for movement therewith, a locking plunger cooperating with the lock rod for locking the switch points in one position, a foot pedal for controlling said lever latch and said locking plunger, a first contact arranged to be operated when said foot pedal is operated, and a second contact arranged to be operated when one of said switch points is moved from its normal position. 85
9. The combination with the movable points of a railway switch and a hand throw lever for moving the switch points, of a lock rod attached to said switch points for movement therewith and provided with an opening, a point detector rod attached to the switch point which is closed in the normal position of the switch and provided with a notch, a switch lock comprising a casing provided with guideways which slidably receive said lock rod and said point detector rod, a locking plunger slidably mounted in said casing and biased to a position in which said plunger rod will enter said opening in said lock rod when and only when the switch points are in their normal positions, a rockshaft journaled in said casing, a lever fixed to said rockshaft and operatively connected with said plunger rod, a foot pedal fixed to said rockshaft, a circuit controller comprising a pair of insulated contact members one of which is provided at each end with a fixed contact finger and the other of which is provided at each end with a movable contact finger which cooperates with one of said fixed contact fingers to form a contact, 90
10. In combination with a movable switch point, a lock rod connected with said switch point to move therewith, a foot pedal, a member controlled in part by said foot pedal and movable between a first position in which said member engages said lock rod to lock it against movement and a second position in which said lock rod is unlocked, a contact, and means controlled by said member for operating said contact just before said lock rod becomes unlocked. 100
11. In combination with a movable switch point, a lock rod connected with said switch point to move therewith, a foot pedal, a member controlled by said foot pedal and cooperating with said lock rod for at times locking said switch point in one position, and a contact controlled by said member in such manner that when said member is operated to unlock said switch point said contact will become operated before said switch point becomes unlocked. 110
12. In combination, a lock rod adapted to be connected with the movable point of a railway switch to move therewith and provided with a hole, a member biased to such position that said member will at times enter said hole and prevent movement of said lock rod, a foot pedal for withdrawing said member from said hole, a contact, and means for controlling said contact in such manner that when said foot pedal is operated to withdraw said member from said hole said contact will become operated before said member is fully withdrawn. 115
